UNITED STATES PATENT OFFICE.

EMIL TYDEN, OF HASTINGS, MICHIGAN.

EXTENSION-TABLE LOCK.

1,076,174.

Specification of Letters Patent. Patented Oct. 21, 1913.

Application filed October 14, 1909. Serial No. 522,575.

To all whom it may concern:

Be it known that I, EMIL TYDEN, a citizen of the United States, residing at Hastings, in the county of Barry and State of Michigan, have invented new and useful Improvements in Extension-Table Locks, of which the following is a specification, reference being had to the accompanying drawing, forming a part thereof.

10 The purpose of this invention is to provide an improved machine for locking the extensible end members of an extension table at steps of extension from closed position corresponding to the widths of the 15 filler to be interposed.

It consists in the elements or features of construction shown and described as indicated in the claims.

In the drawings;—Figure 1 is a top plan view of extension table, embodying this invention, the same being shown with the top and one set of slides in part broken away to disclose the operating and controlling devices. Fig. 2 is a similar view of the middle 25 portion of the table, the ends being partly broken away to reduce the figure, showing the top members extended to admit one filler. Figs. 3 and 3^a are sections at the line 3—3 and 3^a—3^a on Fig. 1. Figs. 4 and 4^a 30 are sections at the lines 4—4 and 4^a—4^a on Fig. 2. Fig. 5 is a detail plan view with the top members in the position shown in Fig. 2, but showing the controlling device shifted so as to permit a further step of extension.

35 Figs. 6 and 6^a are sections at the lines 6—6 and 6^a—6^a respectively on Fig. 5, showing the parts extended such additional step. Fig. 7 is a detail section at the line 7—7 on Fig. 1. Fig. 8 is a detail section at the line 40 8—8 on Fig. 1. Fig. 9 is a section at the line 9—9 on Fig. 1, showing the table top members nearly closed together ready to be locked. Fig. 10 is a section similar to Fig. 9, showing the table top members extended 45 one filler width.

This invention may be applied to any extension table having a supporting member, which may be a pedestal and which may be divided as shown, and having two top members which are movable toward and from each other for closing up and extension of the top. The top members 1, 1, are connected with the pedestal 2, which as illustrated, comprises separable parts 2, 2 by 50 55 the customary slides which are shown in form for connecting a divided pedestal;

that is, adjacent to each other for sliding on each other are slides 4, 4, carried by the pedestal members respectively (and herein-after called the "top-slides") slides 5, 5, attached to the top members respectively, constituting the extreme members of the group of four slides being mounted for sliding respectively on the remote sides of the two slides 4, 4, upon the supporting member,— 60 and when the pedestal is divided, as shown, upon one of the parts 2, 2, of such supporting member,—there is mounted for sliding transversely to the slides 4 and 5, and between said slides and the cap or upper end 6 of the pedestals, a controlling bar 7, having a range of sliding movement transversely of the slides 4, and 5, sufficient to shift from the paths of hooks, 8, 8, on the top-slides 5, 5, respectively, to the path of 65 hooks 9, 9, on said slides respectively, certain abutments or teeth of the bar 7. At the closed position of the top members shown in Fig. 1, the hooks 8, 8, have their hook noses 8^a, separated in opposite directions 70 from the teeth or abutments 10, and 11, respectively, a distance equal to a half filler-width and at the normal position of the controlling bar 7,—the position which is shown in Fig. 1,—the teeth 10, and 11, are in the 75 paths respectively of the hooks 8. The hooks 9, 9, are distant outwardly from said teeth 10, and 11, each two half filler widths in opposite directions; and at said normal position of the controller 7, it has standing 80 in the paths of said hooks 9, 9, cam slopes 85 90 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

abutments 10, and 11, of the controller bar 7. If further extension of the table is desired, the operator must shift the controller bar 7 transversely of the slides to bring the 5 cam slopes 12, and 13, into the paths of the hooks, 8, 8, respectively, whereupon both slides 5, can be moved outwardly another half filler width step and the tops will be spread sufficient to admit two fillers and no 10 more, because the movement of the controller bar 7 for bringing the cam slopes mentioned into the path of the hooks 8, 8, brings into the path of the hooks 9, 9, respectively, the abutment 11, and abutment 15 or edge 16, of the bar 7, which stop the hooks at the limit of the half filler width movement mentioned.

In the table illustrated in the drawings, it is contemplated that not more than three 20 fillers will at any time be inserted without extending the pedestal; and for admitting that number of fillers the operator will shift the bar 7 back to its normal position which brings into the path of the hooks 9, 9, respectively, the cam slopes 12, on the inner side and a third cam slope 17, at the outer side of the group of slides under which the bar 7 extends, thus permitting the dogs 9, 9, to ride up over the bar and thence outward 25 to the limit of the extensibility of the slides, which as stated, is three filler widths, the slides being stopped at that limit by the usual familiar stops provided in the slides themselves. It will be observed that by this 30 construction both top members are at all times stopped against extension at the desired points upon the supporting member, and upon one half that member when it is divided; that is both top members are 35 stopped upon the same support and therefore positively stopped with respect to each other, except at the limit or last step of extension when the stopping occurs in the slides. It will also be observed that the 40 necessity for operating the controller bar 7, in the interval between the extension movements for admitting one filler and two fillers operates to prevent inadvertent extension of one top member two half-steps in succession, 45 which would cause the opening to be unequally distributed at opposite sides of the center, and result in overbalancing the table at one end. At the same time it is possible, whenever desired, to extend the table unequally, because the operator can shift the 50 bar 7, between two consecutive movements of the same top member without having in the interval, moved the other top member. The hook-noses of the dogs 8, and 9, are 55 sloped at their outer ends for riding over the bar 7 in closing up the top, which can thus be done without paying any attention to the position of the slide 7; but the cam 60 15 by encountering the handle 14 will restore

the controller 7 to its normal position if it 65 is out of such position.

Inasmuch as the stop device above described for checking the extension of the top members for extending from middle position at step intervals of half filler width 70 are accessible to the operator only when the top members are opened, at least sufficient to admit the hand, they can not be utilized directly for locking the top members at closed position and for that purpose it is 75 necessary when said stop devices are used, to provide means for locking the top members together; suitable top locking devices are shown in the drawings comprising a 80 hook 20 formed on a slide 21 mounted in a hanger bracket 22 secured upon the underside of one of the top members and connected by a link 23 with an operating and locking lever 24, fulcrumed on the underside of the same top member, near the outer end, and 85 adapted to be swung outwardly and upwardly to locked position, thereby drawing the slide 21, outwardly against the resistance of the spring 22^a, which is coiled about the 90 reduced stem of the slide 21, between the shoulder 21^a, caused by such reduction, and the outer bearing of the slide in the hanger 22. On the underside of the other top member, there is pivoted a coöperating hook 95 device 34, for engaging the hook 20, said coöperating device being preferably in the form of a loop having a tail extension 25, which is stopped on the bracket 26, on which the said device 34, is pivoted, so that the 100 said loop can fall by gravity for engagement with the hook 20, but is checked by its tail, so that at its lowest position it is in the path of the sloping upper edge 27, of a switch or guard plate 28, which is pivoted to the slide 21, and extends alongside of the 105 hook 20, having its upper edge located above the point of said hook, where it extends past the same, when the slide is thrust inward by the spring 22^a, said switch or guard plate being lifted to this position by the 110 hook, by the encounter of a tail 29, with which said guard is provided, extending upwardly near the fulcrum of said guard on the slide, and just back of the inner slide bearing of the slide, in the bracket, so that 115 said tail encounters said bearing when the slide is thrust inward by the spring. When the top members are approaching each other the loop 34, rides up on the said sloping edge of the slide 27, of the switch or guard 28, until the cross bar of the loop passes by the 120 upwardly projecting nose of the hook 20, this position being reached before the top members are closed together. The operator then drawing the lever outward to locking 125 position, retracting the slide, first causes the guard to be dropped, letting down the loop into engagement with the hook, and with

the further outward swinging movement of the lever draws the two top members snugly together.

I claim:

5 1. In an extension table which comprises a supporting member and end top members movable relatively to the supporting member toward and from each other for closing up and extension to admit fillers, in combination with such supporting member and end top members, a set of slides connecting the top members and the supporting member, comprising intermediate slides which are fast on the supporting member; and exterior 10 or extreme slides which are fast on the end top members respectively; a bar extending across the set of slides and stopped against movement longitudinally of the supporting member; a plurality of means on each of the 15 20 extreme slides of the set for engaging said bar positioned along the length of the slides at half filler width intervals and offset laterally from each other so as to travel in different paths when the slide is moved, the 25 bar having abutments for encountering said engaging means alternating in a direction transverse of the sides with crossing paths for said engaging means, and means for moving the bar transversely of the slides to 30 shift the registration of said abutments, and crossing paths with the paths of said engaging means respectively.

2. In an extension table which comprises a supporting member and end top members 35 movable relatively to the supporting member for closing up and extension to admit fillers, in combination with such supporting member and end top members; a set of slides for extensibly connecting the top members 40 and supporting member, comprising intermediate slides fast on the supporting member, and outer or extreme slides fast on the top members respectively, a bar mounted on the supporting member below the slides 45 which are fast thereon for sliding transversely of the extension slides, dogs on the extreme slides positioned along the length

thereof at half filler width intervals, consecutive dogs on each slide being offset laterally from each other's paths, the bars having 50 at opposite sides of the set of slides in position for coöperating with the dogs abutments for engagement of the dogs and cam slopes affording crossing paths for the dogs, and means for shifting the bar transversely 55 to reverse the registration of said abutments, and cam slopes with the paths of the dogs respectively.

3. In an extension table which comprises a supporting member and end top members 60 movable relatively to the supporting member for closing up an extension to admit fillers, in combination with such supporting member and end top members, a set of slides for extensibly connecting the top members 65 and supporting member, comprising intermediate slides fast on the supporting member, and outer or extreme slides fast on the top members respectively; a bar mounted on the supporting member below the slides 70 which are fast thereon for sliding transversely of the extension slides, dogs on the extreme slides positioned along the length thereof at half filler width intervals; consecutive dogs on each slide being offset laterally from each other's paths, the bar having 75 at opposite sides of the set of slides in position for coöperating with the dogs abutments for engagement of the dogs, and cam slopes affording crossing paths for the dogs, 80 the bar at one end having an upstanding arm, and a cam at the side of the adjacent slide positioned for encountering said arm at the limit of the closing movement, and adapted by such encounter to force the bar 85 to one limit of its path of reciprocation.

In testimony whereof I have hereunto set my hand at Chicago, Illinois, this 11th day of October, 1909.

EMIL TYDEN.
